US00D913323S

(12) **United States Design Patent** (10) Patent No.: **US D913,323 S**
(45) Date of Patent: **** Mar. 16, 2021**

(54) **DISPLAY SCREEN OR PORTION THEREOF
WITH GRAPHICAL USER INTERFACE**

- (71) Applicant: **Avision Inc.**, Hsinchu (TW)
- (72) Inventors: **Ting-Kuo Chu**, Zhubei (TW);
Hsin-Chen Lee, Hsinchu (TW);
Yu-Ling Chen, Hsinchu (TW);
Yung-Ting Hsu, Hengshan Township,
Hsinchu County (TW)
- (73) Assignee: **Avision Inc.**, Hsinchu (TW)
- (**) Term: **15 Years**
- (21) Appl. No.: **29/681,712**
- (22) Filed: **Feb. 27, 2019**

Related U.S. Application Data

- (63) Continuation-in-part of application No. 29/600,393, filed on Apr. 12, 2017, now abandoned, which is a continuation-in-part of application No. 29/528,550, filed on May 29, 2015, now abandoned.

(57) **CLAIM**

The ornamental design for display screen or portion thereof with graphical user interface, as shown and described.

DESCRIPTION

The single FIGURE is a front view of display screen or portion thereof with graphical user interface showing our new design.

The outermost broke lines illustrate portions of the display screen and form no part of the claimed design. The remaining broken lines illustrate portions of the graphical user interface and form no part of the claimed design.

1 Claim, 1 Drawing Sheet
